UNITED STATES PATENT OFFICE.

CAHM C. HELMAN, OF CLEVELAND, AND GEORGE W. NIXON, OF CANTON, OHIO.

CORD HOLDER AND DISPENSER DEVICE.

1,076,885.

Specification of Letters Patent.

Patented Oct. 28, 1913.

Application filed October 9, 1912. Serial No. 724,804.

To all whom it may concern:

Be it known that we, CAHM C. HELMAN and GEORGE W. NIXON, citizens of the United States, residing at Cleveland and Canton, respectively, in the counties of Cuyahoga and Stark, respectively, in the State of Ohio, have invented certain new and useful Improvements in Cord Holder and Dispenser Devices; and we do hereby declare the following to be a full, clear, and exact description of the invention, such as will enable others skilled in the art to which it appertains to make and use the same.

This invention relates to a cord holder and dispenser, and it more particularly relates to an improved combination cord and pencil holder.

An object of the invention is to provide a convenient and practical means, whereby a salesman or saleslady may carry a reel of wrapping cord or the like, in position for easy access.

Another object of the invention is to provide a device of this character in which the cord may be quickly and easily replaced, when exhausted.

Another object of the invention is to provide a device of this character with a door, and with a combined door catch and cord cutter member.

Another object of the invention is to provide an improved form of friction drag, for preventing the reel from rotating too freely, and for preventing the same from rattling.

Another object of the invention is to provide means for retaining the reel axle in proper position.

Other objects and advantages may be recited hereinafter and in the claim.

In the accompanying drawings, which supplement this specification, Figure 1 is a front elevation view of our improved cord and pencil holder, and, Fig. 2 is a vertical sectional view through the central portion thereof.

In these drawings, in which similar reference characters correspond with similar parts throughout the several views, the casing 5 is preferably of oblate-spheroidal shape, or of the shape of an ordinary watch case. The casing 5 comprises the main body portion 6, and a door 7, said door being hinged to the main body portion at 8, and held in normally closed position by means

of a snap-catch 9, which operates to engage the edge of the door, said door being of thin and somewhat resilient material, so as to spring into a notch 10, indicated in dotted lines, in the catch 9. The snap-catch is formed integrally with a thread or cord cutter of well known design, as indicated at 11. The body 6 is centrally apertured at 12, for the reception of a pivot or reel axle 13, said reel axle being securely fixed within the aperture 12 and having a pointed end 14. The casing door 7 is centrally apertured for the reception of a keeper 15 which is securely fixed in said central aperture of the door and is provided with a central recess for receiving and keeping the pointed end 14 of the axle 13.

A reel or bobbin 16 is provided with a centrally apertured head 17, rotatably seated on the axle 13, and bearing upon the keeper 15, when the door is closed. Thread or cord 18 may be wound upon the bobbin, by any proper means (not shown), and the casing 6 is provided with an outlet aperture 19, for the cord 18, so that any desired quantity of the cord may be unwound from the reel, and severed by means of the cutter 11. It will be seen that the cutter is located on the casing at an angle of approximately ninety degrees from the cord outlet opening, so that after the cord is severed, a sufficient quantity of said cord depends from the casing, to admit of quickly and easily grasping the same, for drawing more of the cord from the reel.

In order to prevent the reel from rattling within the casing, and in order to prevent said reel from rotating too freely, lest the cord should become tangled or wasted, we provide a spring or resilient drag member 20 provided with an aperture through which the axle 13 extends, said drag member being formed on a compound curve on each side of the axle, so as to provide a convexed portion 21 and a convexed portion 22, the portion 21 bearing upon the inner wall of the casing, and the portion 22 bearing upon the reel 16, so that, while the reel may be easily rotated against the action of the drag, by pulling the cord 18, said drag holds the reel against accidental rotation or axial movement.

A hanger member 23 is pivotally connected at 24 to the top of the casing, and

said hanger is formed with an elongated inverted U-shaped hook 25, which may be engaged with a belt or pocket, and thereby carried by the user. It is obvious, however, that any other suitable and proper form of hanger or support 23 may be used for engaging the clothing of a wearer and supporting the casing.

On the front of the door 7, we secure 10 a pencil holder 8, of resilient material, and adapted to retain the pencil by its spring clamping action.

It will be seen that we have provided a 15 device of this character which is fully capable of attaining the foregoing objects, and in a thoroughly practical and efficient manner.

We do not limit our invention to the exact details of construction, combination and 20 arrangement of parts, as herewith illustrated and described, but our invention may only be limited by a reasonable interpretation of the claim.

We claim:—

A dispensing cord holder consisting of a 25 circular casing having a substantially flat side wall, a shaft secured at one end to said side wall and provided with a pointed bearing end, a reel mounted upon said shaft, a compound curved spring positioned on said shaft and bearing against said side wall and said reel to retard the movement of said reel on said shaft, a door hinged to said casing and provided with a bearing adapted to engage the pointed end of the shaft, and a 30 catch carried by the casing and provided with a thread cutter and adapted to hold the door closed.

In testimony whereof we have signed our names to this specification in the presence 40 of two subscribing witnesses.

CAHM C. HELMAN.
GEORGE W. NIXON.
